METHOD AND MEANS FOR DIVIDING, GENERATING, AND TRANSFORMING DIRECT CURRENT VOLTAGES

Leland L. Davis, Stilwell, Kans.

Application January 2, 1951, Serial No. 203,983

6 Claims. (Cl. 171—252)

1

This invention relates to electrical devices and particularly to a combination dynamo and motor having a novel arrangement of parts for transferring electrical current to and/or from the armature thereof whereby to permit a large number of uses of the device including dividing of line voltage, increasing or decreasing voltage and obtaining of differing voltages or currents, each adapted for application to a separate load as desired.

As will hereinafter appear, the electrical apparatus hereof is adaptable for a large number of uses, but one of its most advantageous applications and for which it has been initially developed, is in the field of electrical vehicles such as trolley busses, street cars, elevated lines, subways and the like. As is well known, direct current car operation is in universal use. The car control embodies a controller or rotary switch or contactor group that is operated by the motorman to actuate the impelling motor or motors. The first advance of the control unit connects the motor or motors in series with a starting resistance. As the control is further advanced, the starting resistance is gradually cut out to accelerate the car. Finally, the controller reaches a position connecting the motor or motors directly across the supply line, eliminating the resistance. Only when the motors are connected directly across the supply line (trolley and rail in the case of rail cars, or positive and negative wire in the case of trolley busses) is waste power reduced to a point of rendering such operation relatively economical. Because of accompanying heat that is generated in such systems, a considerable amount of electric energy is wasted in the starting resistors.

One of the primary objects of the present invention therefore, is to provide electrical apparatus for replacing the resistance starting control now used in electrical vehicle systems, the apparatus having means for receiving the line voltage, dividing the same, and operating the vehicle motors through a number of external circuits that may be selectively placed in use by the motorman according to the degree of vehicle acceleration desired.

It is an important object of this invention to provide an electrical device which may or may not have all of the appearances of a conventional dynamo or electrical motor, but differing in winding of the armature thereof, relative arrangement of the commutator segments and brushes, and coupling of external circuits to adapt the same to a large number of uses not heretofore made possible by use of similar devices.

2

Another object of this invention is to provide apparatus taking the form of a combination dynamo and transformer, capable of use either as a conventional dynamo, utilizing the principle of magnetic induction for converting mechanical energy into electrical energy; to provide a plurality of differing voltages as desired in separate external circuits; or for use similar to that of an A. C. autotransformer to either step-up or step-down the voltage.

A further object of this invention is to provide an armature using truly open coil windings in an advantageous and fully novel manner to produce the results above enumerated, together with the production of high mutual inductance between adjacent coils whereby to effect a sharp reduction or cut-off of conduction as the coils emerge from beneath the brushes.

A still further object of this invention is to make possible through novel construction and arrangement of armature coil windings, the provision of an unlimited number of external circuits which may of themselves be adapted for use independently or be used together through one or more conventional couplings to either supply various loads with needed power or to receive electromotive forces and thereupon divide or multiply the same for such use as may be desired.

Other objects of the present invention include the provision of electrical apparatus capable of dividing an impressed voltage into a number of voltages of lower values totaling the impressed voltage; optionally usable to increase an impressed voltage to one or more higher values; operable to commutate voltage and current irrespective of electrical positioning of brushes and magnetic poles; and fully adaptable to change either an alternating current voltage to direct current voltages of differing values or to change a direct current voltage to an alternating current voltage as desired.

In the drawings:

Figure 1 is a star wiring diagram illustrating the armature winding of apparatus for dividing, generating and transforming electrical voltages made pursuant to my present invention.

Fig. 2 is a plane wiring diagram of the armature winding illustrating one possible external circuit arrangement.

Figs. 3, 4 and 5 are views similar to Fig. 2 showing other external circuit arrangements.

Fig. 6 is a view similar to Fig. 2, showing progressively different relative positions of brushes and commutator segments.

Fig. 7 is a graph showing the relationship of

current in an external circuit with that of the armature coils of a uniformly loaded apparatus, and with the armature mechanically driven.

Fig. 8 is a schematic view corresponding to Fig. 2 showing the manner of loading to produce the relationship of Fig. 7.

Fig. 9 is a graph showing the relationship of current in various armature coils with load connected to one armature coil and with armature operating as a motor taking current from a supply line.

Fig. 10 is a schematic view corresponding to Fig. 9 showing the manner of loading to produce the results of Fig. 9.

Fig. 11 is a fragmentary view showing a modified form of commutator-brush arrangement; and

Fig. 12 is a fragmentary view showing another form of commutator-brush arrangement.

As above indicated, the apparatus hereof may be quite conventional from the standpoint of appearance and mechanical construction. As in any generator or motor, there is provided a field frame mounted on a suitable base and carrying the field coils and their shoes therewithin; end frames each provided with a bearing for rotatably supporting an armature shaft; a commutator on the shaft and coupled with the windings of the armature; brush holders carried by one of the end frames for holding the brushes in engagement with the commutator; external circuits, and brush connections; and such other auxiliary fixtures as is quite common in this field. The mechanical construction of such parts forms no part of this invention however, and has not been shown.

In the drawings there is shown a pair of poles 20 and 22 of opposite polarity, to produce a magnetic field, preferably using electromagnets as is customary. The legs of the magnets, the ends of which form poles 20 and 22, are so disposed that an armature, broadly designated by the numeral 24, revolves between them and within the lines of flux forming the magnetic field.

While a bipolar arrangement is illustrated, this invention contemplates use of as many electromagnets as is desired since it may well be advantageous to include the features hereof in multipolar design, particularly in larger machines.

The method of field excitation may also be chosen as desired, i. e., either self-excited or separately excited. In the latter, current that is caused to flow into the field magnet coils is impelled by an outside source separate from the device itself. In self-excitation, current may be impelled by armature 24 through any one of a number of common field winding arrangements, including series, shunt, or compound windings.

The armature 24 is provided with a core upon which are mounted a plurality of truly open, preferably drum wound separate coils 26 for generating an E. M. F. as armature 24 is rotated within the magnetic field so that the lines of flux thereof are cut by inductors 36 forming a part of the open coil windings 26. Each coil 26 may include as many turns as desired depending upon the number of cutting conductors required, but in each case the inductors 36 are disposed or spaced approximately 180 electrical degrees apart as illustrated.

For reasons hereinafter to be made more clear, armature 24 differs also from conventional direct current machines having commutators in that the mutual coupling between coils 26 should be

as high or close as possible to produce high mutual inductance therebetween.

There are shown in the drawing for purposes of illustration only, ten identical open coils 26, designated 26a and 26j inclusive, and each having a pair of segment connections.

Commutation or rectification is produced by means of a commutator broadly designated by the numeral 32, provided to change the alternating E. M. F. or current output of armature 24 to direct E. M. F. or current as is customary in devices of this character. Twenty metallic segments or bars, separated by suitable insulation form the commutator 32, there being a segment for each of the connections 34 respectively. The segments are designated by the letters a to t inclusive and are mounted for rotation with armature 24. Segments a—t of commutator 32 are joined directly to the corresponding ends of inductors 36 by connections 34.

It is seen therefore, that coils 26a—26j do not as a whole form a closed circuit upon themselves with the commutator segments to which they are connected and that each coil does not always form a part of a closed circuit. Each coil instead is in circuit only when the commutator bars thereof contact a pair of brushes 38. The ten brushes shown are designated 38a to 38j inclusive in the drawings.

It is noted that brushes 38 are arranged in pairs spaced 180 electrical degrees, i. e. brush 38a is opposed to brush 38j, brush 38b is opposed to brush 38g, etc. Accordingly, when any one brush 38 is in full contact with a segment of commutator 32, its opposed brush is in full contact with the opposite commutator segment of the same coil 26.

For instance, as shown in Figs. 1 and 2, when brush 38c is in full contact with segment f of coil 26d, the opposed brush 38h is in full contact with segment p of coil 26d. However, when the commutator 32 of armature 24 is positioned relative to brushes 38 as shown in Figs. 1 and 2, only one-half of the coils 26 are contacted by brushes 38, the other half of the coils being fully inactive and out of circuit. In other words, since all of the coils 26 are separately insulated and all of the commutator segments separated by insulation, no current will flow in the inactive coils though voltage is induced thereinto. Thus, for example, segments e and o of coil 26c have no brush contact, and this coil, together with coils 26a, 26e, 26g and 26i, are all out of circuit. Coils 26b, 26d, 26f, 26h and 26j are all in circuit by such direct contact between their commutator segments and corresponding brushes 38.

In Figs. 1 and 2, each brush 38 of each of the five pairs thereof is series-coupled with one of the brushes 38 of another pair by a conductor for connection with an external circuit. A conductor 42 couples brush 38b with brush 38j; brushes 38c and 38i are joined by a conductor 44; a conductor 46 connects brushes 38d and 38g; and a conductor 48 joins brush 38e with brush 38f.

Shunt field coils 50 are shown coupled across brushes 38a and 38h through terminal points 52 and 54 and conductors 40. Lead lines 56, 58, 60 and 62 join with conductors 42, 44, 46 and 48 respectively.

Assuming D. C. line current to be coupled with terminals 52 and 54, the series connection of five of the coils 26 may be traced in Figs. 2 and 3 as follows:

From terminal 52 through conductor 40, brush 75 38a, segment b, coil 26b, segment l, brush 38f,

conductor 48, brush 38e, segment *j*, coil 26*f*, segment *t*, brush 38*j*, conductor 42, brush 38*b*, segment *d*, coil 26*h*, segment *n*, brush 38*g*, conductor 46, brush 38*d*, segment *h*, coil 26*j*, segment *r*, brush 38*i*, conductor 44, brush 38*c*, segment *f*, coil 26*d*, segment *p*, brush 38*h*, and conductor 40 to terminal 54.

Obviously, when the commutator 32 moves from the position shown in Figs. 1 and 2 to a point where the remaining segments thereof are in full contact with the ten brushes, the five coils just above mentioned will become inactive and the remaining five coils will be placed in a series circuit with the line current coupled with terminals 52 and 54 and will carry current equal to the line current, but at different relative voltages.

Consequently, current will flow into any load or combination of loads connected between any pair or combination of pairs of lines 56, 58, 60, 62 or terminals 52—54.

As soon as the commutator 32 moves to a position where each adjacent pair of segments thereof engages a brush, all of the coils 26 become active and carry current, there being two groups of five coils 26 each, joined in parallel and series coupled within the respective group. Again, by virtue of insulation separating the commutator segments, each pair of coils carries a different relative voltage. In Fig. 6, the brushes 38 are shown each making half contact with a pair of adjacent segments of commutator 32 and each coil 26 therefore, carries current equal to approximately one-half of the line current directed to conductors 40.

The relationship of current in the main line coupled with conductors 40 (see Fig. 8) and the adjacent coil groups 26 is shown in Fig. 7, one complete armature revolution being indicated along the abscissa of the graph. Lines 64 and 66 represent no current flow and maximum line current respectively. Full lines 68—70 refer to current flow in one group of five coils 26 while dash lines 72—74 refer to current flow through the remaining five coils 26.

It is seen that as the ten commutator segments of five of the coils 26 commence to engage the ten brushes 38, the current flow thereof rapidly rises as indicated by lines 68 from zero line 64, reaching maximum current flow as indicated by line 66 when the ten segments are in full contact with the brushes.

At the same time the remaining segments are leaving the brushes with a drop in current flow in the coils thereof as shown by lines 74. Thus, the output of all external circuits remains substantially constant, the sum of the currents represented by lines 68 and 74 being equal to the current indicated by line 66 and induced into the system through conductors 40. Curve 76 of Fig. 7, indicates magnetization of field poles 20 and 22.

In Fig. 10 of the drawings the induced voltage is shown across brushes 38*h* and conductor 48 and a large load is coupled with brush 38*h* and line 58. No current flows through brush 38*a* and the current through the coil having a segment engaged by such brush 38*a* is zero. Through such external tapping the instrument operates similarly to an autotransformer with the current in the load across brushes 38*i* and 38*h* approximately three times that of the supplied current. The current in the coil that is connected through its commutator segments with brushes 38*h* and 38*c*, is approximately double that of the other active coils.

Referring to Fig. 9 and following the current flow to a segment as the same passes from brush to brush, it is obvious that such current flow is zero whenever the segment is in engagement with brush 38*a*. The coil current rises to a maximum value as indicated by line 78 when the segment is in engagement with brush 38*b*; reverses and rises to double the supplied current value under brush 38*c* as indicated at 79; reverses again and rises to supplied current value 78 under both brushes 38*d* and 38*e*; falls to zero when engaging brush 38*f* because of the disconnection of brush 38*a*; rises to line current value 78 under brush 38*g*; reverses and rises to approximately double the value of the supplied current when engaging brush 38*h*; and reverses again and rises to the value of the supplied current under both brushes 38*i* and 38*j*. Curve 81 indicates current flowing in the load circuit 54—58 in Fig. 10.

It is seen that upon rotation of the armature 24, supplying current to a load, each coil 26 of the armature 24 supplies an impulse current to the load as it passes under a brush 38. The following coil 26 thereupon picks up the impulse as it passes under the brush. As each coil 26 passes under a pole 20—22 of given polarity, the current flow therethrough is composed of a series of pulses in a given direction. As soon as the coil leaves such pole and passes under a pole of reversed polarity, the current pulses reverse direction but so long as a coil is under the influence of either pole, it maintains a voltage across its respective commutator segments 32 in a definite direction. The rise and fall of current in the coils is continuously repeated but in alternately reversed directions as polarity reverses. Accordingly, the current flowing in the external circuits is continuous and made up of current pulses.

It is clear from the foregoing that the device of Figs. 1 and 2 may be used either as a dynamo, as an electric motor or as a transformer. When used to operate from a D. C. line appropriate terminals 52, 54, 56, 58, 60 or 62 are connected to the supply line as above indicated. Line voltage is thereupon impressed upon a portion or all of the commutator 32 depending upon the coupling with the supply line. The armature 24 will thereupon act as a motor revolving and taking energy from the D. C. supply line. Divided voltages will appear across the remaining terminals and the loads connected thereacross will receive energy from the D. C. supplied line but at differing voltages. In this respect therefore, the device is operable as an autotransformer on a D. C. supplied line to reduce or increase the supply voltage as desired.

It is seen that one or more voltages higher than the impressed supply voltage may be produced; one or more voltages each of a lower value than the impressed voltage may be connected to various loads and that through proper coupling of the supply line voltage to the external circuits of the apparatus, the same may be used both as a voltage increase and a voltage decrease device simultaneously.

Obviously, the device may be driven mechanically in the same manner as a conventional generator through rotation of the armature 24 by means of an auxiliary prime mover connected with the shaft of the armature 24. In this case the instrument will develop a plurality of voltages across its brush terminals. Similarly, when operating as a generator through driving of armature 24, auxiliary line voltage may be impressed

on any of the terminal connections to produce a large number of desired results.

When operating as a motor to transform a plurality of voltages, the armature 24 could conceivably be connected through its shaft with any motor driven device to be motivated in the conventional manner.

If alternating current operation is desired, slip rings (not shown) may be added to the shaft of armature 24 and connected to the coils 26 in the conventional manner for feeding into the machine alternating E. M. F. for motor operation or taking from the machine alternating E. M. F. for use in an external circuit. By using a pair of slip rings for each phase, any number of phases may be impressed on the machine up to the limit of the number of coils 26 on the armature 24. The same phase relationship would, of course, have to be maintained in connecting the armature coils 26 as that of the A. C. supply line. For example, two-phase operation would require 90 electrical degree connection to armature coils 26 and similarly, 6 phase diametrical connection would require a 60 electrical degree relationship.

In conventional direct current machines, it is desirable to hold mutual inductance between the armature coils to a minimum in order to minimize sparking and burning of brushes as the armature coils undergo commutation. The converse is desired in the present machine in order to induce the reverse action in the adjacent coils 26. As current builds up in a particular coil 26 when its segments move into engagement with pairs of brushes 38, inductive action reduces the voltage in adjacent coils 26 emerging from under such brushes producing therefore, better commutation.

It is now also seen that the device hereof is particularly adaptable for use in transit systems, powered by D. C. motors to replace starting resistors now commonly used and thereby reduce electrical energy waste in the form of heat. While the machine may have many other applications wherever multi D. C. voltages or divided D. C. voltages are required, its application to provide a number of progressively increased voltage levels for starting D. C. motors in streetcars and other electrically powered vehicles or machines of all kinds, is perhaps one of its most important uses. Such heavy duty motors are commonly employed in the operation of elevators, propulsion of ships, driving of electric trucks, rolling mills and many other electrical devices. Desired D. C. voltage either of greater value or of lesser value than that of the line supply may be applied through use of the machine hereof to various contrivances including lamps, motors, projectors, radios and the like. Intermediate grounding of a D. C. voltage such as may be required by a three-wire Edison system or other related circuits, presents another advantageous use of the machine above described.

The machine presents a method of dividing impressed D. C. voltages into sub-voltages of lower values, the sum of which equal the impressed voltage; a method of increasing the impressed D. C. voltage to a higher value or values; the method of generating D. C. voltages of several independent values by mechanically rotating the armature 24; and a method of changing A. C. voltage to multi-value D. C. voltages, or conversely for changing D. C. voltage to A. C. voltage.

While the above description contemplates an illustrated device wherein the brushes 38 are

separated by a single segment or bar of commutator 32, one modification that is possible is illustrated in Fig. 11 of the drawing wherein a pair of commutator segments 100 separate brushes 102 whenever the latter are in full engagement with one segment 100. Similarly, in Fig. 12, another modification is illustrated wherein each brush 104 is capable of full engagement with two commutator segments 106 at the same time while brushes 104 are separated by two or more of the segments 106.

The modifications thus far considered have been limited to series connected brushes in external circuits, but it is obvious that the novel armature constructions hereof permits of infinite other coupling arrangements.

In Figs. 3 to 5 inclusive, commutator 32 and brushes 38 are shown, using the same designations as in Figs. 1 and 2; and the coils 26 join the segments of commutator 32 in the same manner as above described.

Independent external circuits are shown in Fig. 3, there being shown in this particular arrangement external circuits equal in number to one-half the number of open coils 26. The first independent circuit is composed of lines 200 and 202 connected with brushes 38a and 38f respectively. Lines 204 and 206 join brushes 38c and 38h respectively, forming a second circuit. The third external circuit joins brushes 38e and 38j by lines 208 and 210 respectively. Lines 212 and 214 connect with brushes 38b and 38g and lines 216 and 218 couple with brushes 38d and 38i to form the fourth and fifth circuits.

It is noted that when the device is as shown in Fig. 3, one circuit may be traced from line 200 through brush 38a, commutator segment 32b, the corresponding coil 26, segment 32L, and brush 38f to line 202. The remaining four circuits are traceable similarly. When segment 32a moves under brush 38a and segment 32k moves under brush 38f, the coil between segments 32a and 32k becomes active with respect to the circuit 200—202.

Thus, the coils are alternately active and inactive as in the form of Figs. 1 and 2. With rotation of the armature, each of the coils 26 will successively become active and then inactive with respect to each of the successive brushes 38a to 38j, and each external circuit is continually energized with pulsating D. C. energy by the coils 26 moving successively into series with the respective brushes 38 thereof.

A parallel arrangement of external circuits is shown by Fig. 4, one of which is traceable as follows:

From a lead line 220 to line 224, brush 38f, segment 32L, a coil 26, segment 32b, brush 38a and line 222 to lead line 226, and:

From line 220 to line 228, brush 38g, segment 32n, a coil 26, segment 32d, brush 38b and line 230 to line 226.

Another arrangement shown in Fig. 4 is traced as follows:

From lead line 232, through line 234, brush 38j, segment 32t, a coil 26, segment 32j, brush 38e, and line 236, to lead line 233, and:

From line 232, line 240 and 242, brush 38i, segment 32r, a coil 26, segment 32h, brush 38d and lines 244 and 246 to line 238, and:

From line 232, to lines 240 and 248, brush 38h, segment 32p, a coil 26, segment 32f, brush 38c, and lines 250 and 246 to lead line 238.

It is noted that in the parallel circuit first traced, two coils 26 are coupled in parallel

through the brushes 38 to either feed the external circuit including lines 220 and 226 or receive energy therefrom. Here again half of the coils are inactive when the commutator 32 is positioned as shown in Fig. 4 and half are active. The current capacity of this circuit is therefore, increased by the parallel coupling.

In the last-mentioned circuit, three coils are coupled in parallel and the current capacity of the external circuit including lines 232 and 238 is increased accordingly.

Fig. 5 shows how the open coil structure permits use of both series and parallel external circuits coupled for possible advantageous uses.

First there is shown in Fig. 5 a parallel, external coupling identical with that of Fig. 4 wherein three coils 26 are joined in parallel. Thus, the same designating numerals are used including lead lines 232 and 238.

Additionally, there is provided a pair of series-connected coils 26 joined in series with such 3-coil parallel arrangement, traceable as follows:

From lead line 238 to line 252, brush 38f, segment 32L, a coil 26, segment 32b, brush 38a, line 254, brush 38g, segment 32n, a coil 26, segment 32d, and brush 38b to lead line 256.

Thus a circuit including lines 232 and 238 has greater current capacity than a circuit including lines 238 and 256.

In summary therefore, it is now apparent that the electrical apparatus hereof, making use of coil windings that are in no way connected except by external circuit arrangements, permits an extremely wide range of adaptations, particularly when it is realized that but a few possible connections have been illustrated and described.

All of the forms contemplated hereby have the open-coil arrangement in common with each coil provided with a pair of commutator segments connected to the ends thereof. Thus, there must always be an even number of segments 32. The number of coils and the number of turns for each may however, vary. And the number of pairs of field poles may be selected as desired.

Also, the brushes 38 must be even in number but not necessarily half as many brushes 38 as segments 32. Each brush may be capable of spanning a full segment as in Fig. 2, two or more segments as in Fig. 12, or only part of a segment. Further, one brush of the series thereof may be capable of full contact with but one segment while other brushes in the same device may be of such size as to span the distance between two or more commutator segments.

It is preferable however, that the relationship between each brush and proximal segments at any given point in the cycle of operation be the same as the relationship between other brushes and their proximal segments.

Thus, for example in Fig. 2, when a given brush is in full contact with one segment all of the remaining brushes should likewise be in full contact with one brush. By way of further example in a modification where at least some of the brushes are capable of covering two commutator segments, under such condition all of the remaining brushes should cover or full contact at least one segment at any given instant in the cycle of operation.

Also, while in virtually all of the systems above outlined, one-half of the coils are active and the other half inactive during a given condition of operation, such may also be modified. One example is shown in Fig. 11 where two coils are inactive while adjacent coils are conducting.

Having thus described the invention what is claimed as new and desired to be secured by Letters Patent is:

1. In an electrical device, field structure including at least one pair of field magnets having poles of opposite polarity for producing a magnetic field; an armature having a number of open-coil, electrical windings mounted thereon, said armature and said field magnets being relatively rotatable and said windings being disposed to cut lines of magnetic flux produced by said field as the armature and the magnets rotate relatively; a commutator connected to said armature and provided with a plurality of conductible segments having insulating means separating the same, there being a segment joined to each end respectively of each of said windings presenting a number of pairs of segments, the segments of each pair thereof being spaced approximately 180 electrical degrees; a number of pairs of separate, conductible brushes, the brushes of each pair thereof being spaced approximately 180 electrical degrees, said brushes and the commutator being relatively rotatable, said brushes being disposed for successive engagement with the commutator segments of the windings; and means adapting the brushes for connection with external circuits, each brush being always in engagement with at least one segment.
2. In an electrical device, field structure including at least one pair of field magnets having poles of opposite polarity for producing a magnetic field; an armature having a number of open-coil, electrical windings mounted thereon, said armature and said field magnets being relatively rotatable and said windings being disposed to cut lines of magnetic flux produced by said field as the armature and the magnets rotate relatively; a commutator connected to said armature and provided with a plurality of conductible segments having insulating means separating the same, there being a segment joined to each end respectively of each of said windings presenting a number of pairs of segments, the segments of each pair thereof being spaced approximately 180 electrical degrees; a number of pairs of separate, conductible brushes, the brushes of each pair thereof being spaced approximately 180 electrical degrees, said brushes and the commutator being relatively rotatable, said brushes being disposed for successive engagement with the commutator segments of the windings; and means adapting the brushes for connection with external circuits, each brush being always in engagement with at least one segment.
3. In an electrical device, field structure including at least one pair of field magnets having poles of opposite polarity for producing a magnetic field; an armature having a number of open-coil, electrical windings mounted thereon, said armature and said field magnets being relatively rotatable and said windings being disposed to cut lines of magnetic flux produced by said field as the armature and the magnets rotate relatively; a commutator connected to said armature and provided with a plurality of conductible segments having insulating means separating the same, there being a segment joined to each end respectively of each of said windings presenting a number of pairs of segments, the segments of each pair thereof being spaced approximately 180 electrical degrees; a number of pairs of separate,

11

conductible brushes, the brushes of each pair thereof being spaced approximately 180 electrical degrees, said brushes and the commutator being relatively rotatable, said brushes being disposed for successive engagement with the commutator segments of the windings; and an external circuit for each pair of brushes respectively, said circuits and the brushes thereof being arranged relative to the segments for successive connection of the windings in series with the circuits.

4. In an electrical device, field structure having means for producing a magnetic field; an armature having a number of open-coil, electrical windings mounted thereon, said armature and said field structure being relatively rotatable and said windings being disposed to cut lines of magnetic flux produced by said field as the armature and the field structure rotate relatively; a commutator connected to said armature and provided with a plurality of conductible segments having insulating means separating the same, there being a segment joined to each end respectively of each of said windings presenting a number of pairs of segments; a number of pairs of separate, conductible brushes, said brushes and the commutator being relatively rotatable, said brushes being disposed for successive engagement with the commutator segments of the windings; and means adapting the brushes for connection with external circuits, each brush being always in engagement with at least one segment.

5. In an electrical device, field structure including at least one pair of field magnets having poles of opposite polarity for producing a magnetic field; an armature having a number of open-coil, electrical windings mounted thereon, said armature and said field magnets being relatively rotatable and said windings being disposed to cut lines of magnetic flux produced by said field as the armature and the magnets rotate relatively; a commutator connected to said armature and provided with a plurality of conductible segments having insulating means separating the same, there being a segment joined to each end respectively of each of said windings presenting a number of pairs of segments, the segments of each pair thereof being spaced approximately 180 electrical degrees; a number of pairs of separate, conductible brushes, the brushes of each pair thereof being spaced approximately 180 electrical degrees, and being disposed for engagement with the commutator segments, said brushes and the commutator being relatively rotatable; and an external circuit including electrical con-

12

ductors joining one brush of one pair thereof in parallel with one brush of at least one other pair thereof, said circuit and the brushes thereof being arranged relative to the segments for successive connection of said windings in parallel with the conductors.

6. In an electrical device, field structure including at least one pair of field magnets having poles of opposite polarity for producing a magnetic field; an armature having a number of open-coil, electrical windings mounted thereon, said armature and said field magnets being relatively rotatable and said windings being disposed to cut lines of magnetic flux produced by said field as the armature and the magnets rotate relatively; a commutator connected to said armature and provided with a plurality of conductible segments having insulating means separating the same, there being a segment joined to each end respectively of each of said windings presenting a number of pairs of segments, the segments of each pair thereof being spaced approximately 180 electrical degrees; a number of pairs of separate, conductible brushes, the brushes of each pair thereof being spaced approximately 180 electrical degrees, and being disposed for engagement with the commutator segments, said brushes and the commutator being relatively rotatable, a first external circuit including electrical conductors joining one brush of one pair thereof in parallel with one brush of at least one other pair thereof, said circuit and the brushes thereof being arranged relative to the segments for successive connection of said windings in parallel with the conductors of said circuit; and electrical conductors joined with a third pair of said brushes to present a second external circuit, said second circuit being arranged relative to the segments for successive connection of said windings in series, said first external circuit and said second external circuit and their respective brushes being arranged relative to the segments for successive connection in series-parallel of said windings throughout operation of the device.
